No Drawing. Application March 18, 1940, Serial
No. 324,722. In Germany March 18, 1939

11 Claims. (Cl. 252—109)

The present invention relates to washing and cleaning compositions, characterized by their content of such products which form from simple aliphatic amines or those, the alkyl group of which is substituted, for example by hydroxyl, aryl, aralkyl or cycloalkyl groups, if brought to reaction with phosphoric acids poorer in water than orthophosphoric acid.

The efficiency of soaps and saponaceous compositions, for example sulphonated oils, as washing agents is impaired by the fact, that in hard water these bodies form insoluble or slightly soluble calcium and magnesium soaps, reducing the foaming and washing power of the soap, and moreover attacking the washed goods by deposition of soaps of the alkaline earths. Also with toilet soaps the lime soap deposition is inconvenient, involving not only a higher soap consumption with imperfect, insufficient cleaning effect, but affecting also the skin of sensitive persons.

Efforts have been made in order to eliminate this disadvantage, by adding to the washing and cleaning agents water-soluble salts of phosphoric acids poorer in water than orthophosphoric acid, especially alkali metal meta- and polyphosphates, thus preventing the lime soap formation and consequent damages. But the addition of said salts, especially sodium salts, to liquid soaps brings another disadvantage: the turbidity point is thereby essentially raised, and the obtained solutions are not clear owing to an exchange of ions and conversion of the liquid potash soaps into sodium soaps. The incorporation of potassium salts, however, causes technical difficulties, as the latter are slightly soluble and make the solution turbid.

It has been found that these disadvantages of the above mentioned potassium and sodium salts of phosphoric acids can be eliminated by incorporating products which form from simple aliphatic amines or those, the alkyl group of which is substituted, for example by hydroxyl, aryl, aralkyl or cycloalkyl groups, if brought to reaction with phosphoric acids poorer in water than orthophosphoric acid. In this way solid, semi-solid or liquid soaps or their solutions are obtained, according to the consistency of the initial products employed. The aqueous solutions of such washing agents have not only the quality of remaining liquid even at very low temperatures, but, in addition to that, of having improved foaming power and reduced tendency to form calcium deposits. Products as claimed by the present invention form, when reacting for instance 110 g. of monoethanolamine with 80 g. of metaphosphoric

acid with or without cooling. Quantity and proportion may also be varied. The resulting acid products may be adjusted neutral or alkaline by an excess of amine or by addition of alkali or ammonium hydroxide. Instead of monoethanolamine other substituted amines, for example di- and triethanolamine and the corresponding propanol- and butanolamines, or quaternary ammonium compositions may be applied, and instead of metaphosphoric acid subphosphoric acid, pyrophosphoric acid or polyphosphoric acid may be used.

Example 1.—Add to a liquid potash soap with about 15% fatty acid 5 or 10% of the product resulting from reacting 110 g. of monoethanolamine with 80 g. of anhydrous phosphoric acid. The obtained soap has a good foaming power and reduced tendency to form calcium deposits. It remains clear even at temperatures about the freezing point.

Example 2.—Add to a liquid potash soap with about 15% fatty acid 10% of the aminephosphate, prepared as in Example 1, and 10% of sodium hexametaphosphate. A soap solution is obtained, which even at low temperatures does not become turbid and shows an excellent washing and foaming power as well as reduced tendency to form calcium deposits.

Example 3.—Stir 80 g. of polymeric metaphosphoric acid under cooling into 100 ccm. of a 33% aqueous solution of polymeric metaphosphoric acid. By addition of alcohol the end product is precipitated from the so obtained clear, viscous solution in form of a white, syrupy mass. Neutralization follows in the usual manner with either alkali lye or amine. The obtained product is then incorporated into the soap.

Instead of adding aminephosphate and alkali metal phosphate subsequently, the latter for example may already be added at the manufacture of soap, and the product formed from phosphoric and substituted amines may be incorporated afterwards or inversely. The separately prepared soap solutions may also be mixed with the new products on the one hand and with the alkali metal salts of phosphoric acids poorer in water than orthophosphoric acid on the other hand.

It has formerly been tried to obtain lime-dissolving products by addition of ethanolamine to sodium hexametaphosphate-containing soaps. The desired effect did not appear. It is therefore obvious that the efficiency of the new products surpasses that of the known soap-improving compositions, a phenomenon which cannot be explained to be a simple combination effect.

Moreover, the present process is simple and generally applicable, combined with the further advantages, that the products have a better cleaning effect and are economic in consumption. Finally, it is possible by the new products to add also to liquid soaps, lime soap-preventing metaphosphates.

What we claim is:

1. A washing and cleaning composition which does not produce deposits and turbidity in hard waters, comprising a potassium soap in which is incorporated the reaction products resulting from the reaction between phosphoric acids, containing less water in the molecule than orthophosphoric acid, and aliphatic amines, selected from the class consisting of the simple aliphatic amines and aliphatic amines substituted with hydroxyl, aryl, aralkyl and cycloalkyl groups.

2. A washing and cleaning composition which does not produce deposits and turbidity in hard waters, comprising a potassium soap in which is incorporated an organic amine salt of a phosphoric acid which contains less water in the molecule than orthophosphoric acid.

3. A washing and cleaning composition which does not produce deposits and turbidity in hard waters, comprising a potassium soap in which is incorporated an organic amine salt of a phosphoric acid which contains less water in the molecule than orthophosphoric acid, as well as a sodium salt of such a phosphoric acid.

4. The product of claim 2 wherein said organic amine salt is the monoethanolamine salt of said phosphoric acid.

5. The product of claim 3 wherein said organic amine salt is the monoethanolamine salt of said phosphoric acid.

6. A process of producing potash soaps which do not give rise to deposits and turbidity in hard water, characterized by the feature that a reaction product of an aliphatic amine with a phosphoric acid, which is poorer in water than orthophosphoric acid, is incorporated into a potash soap.

7. A process of producing potash soaps which do not give rise to deposits and turbidity in hard water, characterized by the feature that a reaction product of a simple, unsubstituted aliphatic amine with a phosphoric acid, which is poorer in water than orthophosphoric acid, is incorporated into the potash soap.

8. A process of producing potash soaps which do not give rise to deposits and turbidity in hard water, characterized by the feature that a reaction product of a phosphoric acid, which is poorer in water than orthophosphoric acid, with an aliphatic amine, selected from a class consisting of the simple aliphatic amines and aliphatic amines substituted with hydroxyl, aryl, aralkyl cycloalkyl groups, is incorporated into a potash soap.

9. A process of producing potash soaps which do not give rise to deposits and turbidity in hard water, characterized by the feature that a reaction product of monoethanolamine with a phosphoric acid, which is poorer in water than orthophosphoric acid, is incorporated into the potash soap.

10. A process of producing potash soaps which do not give rise to deposits and turbidity in hard water, characterized by the feature that a reaction product of an aliphatic amine with a phosphoric acid, which is poorer in water than orthophosphoric acid, as well as a sodium salt of such a phosphoric acid are incorporated into a potash soap.

11. A washing and cleaning composition which does not produce deposits and turbidity in hard waters, comprising a liquid potassium soap and the reaction products resulting from the reaction between a phosphoric acid, which contains less water in the molecule than orthophosphoric acid and monoethanolamine.
